H. KRUG ET AL

WINDOW SASH LOCKING AND VENTILATING DEVICE

Filed March 10, 1922

Inventors
Henry Krug and Joseph Dodd,
by John Elmer Jones,
Attorney.

UNITED STATES PATENT OFFICE.

HENRY KRUG AND JOSEPH DODD, OF CINCINNATI, OHIO.

WINDOW-SASH LOCKING AND VENTILATING DEVICE.

Application filed March 10, 1922. Serial No. 542,701.

To all whom it may concern:

Be it known that we, HENRY KRUG and JOSEPH DODD, both citizens of the United States of America, and residents of Cincinnati, in the county of Hamilton and State of Ohio, have invented a certain new and useful Improvement in Window-Sash Locking and Ventilating Devices, of which the following is a specification.

Our invention relates to window ventilators, and has for one of its objects to regulate the ingress of air through the spacing-arrangement of the meeting-rails of the sash-members by means of detachable clamping devices and suitable top and bottom spacing-plates, wherein the adjustable mechanism of said clamping devices will position the free-end portion of the meeting-rails in predetermined points to allow the current of air to freely pass through the draft openings.

Another object of this invention is to provide a rigging which is simple in construction, effective and positive in operation, and comprises a structural combination for a ready and substantial connection with the sash-members.

In the accompanying sheet of drawings, Figure 1 is a sectional fragmentary vertical section of a window, showing the two sashes thereof and the attached air-regulating device; Fig. 2, an elevation of the regulating device detached; Fig. 3, an enlarged perspective of the sliding, segmental, registering plate or hub; Fig. 4, an enlarged perspective view of the angular plate or base-member; Fig. 5, an enlarged perspective view of one form of spacing-plate adapted for use with our invention herein; Fig. 6, an elevation of another form or a modification of the said spacing-plate; Fig. 7, a plan view of Fig. 6, showing the interposed connecting-plate; and Fig. 8, a horizontal section, on the line 8-8, of Fig. 3. Mounted on the external body-portion of the sash-casing 1 is a series of staples 2 in spaced-relation to each other, slidably-engaging the inturned-end hooks 3 of the right-angled bar-arm 4. Slidably-arranged upon the vertical portion of said bar-arm 4 is a longitudinally-disposed semi-cylindrical member 5 that has laterally-extending flange-members 6 and inwardly-extending tongues 7, the latter freely engaging vertical grooves 8 made along the peripheral side of the said

vertical portion of the bar-arm 4. The base-plate 10, that comprises a transversely-curved part, with suitably-threaded bores 11 and 14 at its opposite ends, is provided with side notches 9 to receive the lower ends of said flange-members 6 of the slide-member 5, for anchoring-means in their vertical, reciprocating movements for linear-adjustment. The threaded terminal of the said vertical portion of the bar-arm 4 is carried by the internally-threaded bore 11 in the base-plate 10 in clamping-relation to the lower end of the meeting-rails 15 by means of the clamping-bolt 16 and thumb-nut arrangement 13. The predetermined position of the staples 2 and the inturned hook 3 will cause a diverging position of the meeting-rails in open relation to each other (as shown in Fig. 1), to admit and exhaust the air-currents for ventilating purposes, as shown by the curvilinear-path of the arrow-line 17 in Fig. 1.

To eliminate an eventual frictional-engagement of the thumb-nut equipped bolt 13 with the glass-portion 18, the bore 14 in the base-plate 10 is in an inclined position to allow the thumb-nut 13 an angular-displacement for clamping purposes. The closure members or spacing-plates 19 and 20, interposed beneath or above the top and bottom rails of the respective upper and lower sashes, will cover all apertures created by the above-described adjustment.

The spacing device, seen in Figs. 6 and 7, is especially adapted for use in connection with our invention herein and is composed of a short member 19 (to the right), and a long member 19^a (to the left), an open slot 22 being provided in the inner end of the member 19, and a metal plate 23 extending from the inner end of member 19^a for engaging said slot 22 in uniting the two members 19 and 19^a for longitudinal extension or adjustment to suit different widths of window-openings and to allow the member 19 to be interchangeable, a longer or shorter member 19 being readily adapted to be detachably-connected with the plate 23 when occasion requires. This spacing-member is not specifically claimed herein but it otherwise forms the subject-matter of a later application for patent.

Certain of the details of construction, shown herein, can be varied according to individual preference and special conditions

without departing from the spirit and essence of the invention as defined in the appended claim.

We claim:—

- 5 In a device of the character described, the combination with the meeting-rails of a window, of a horizontal arm or base-member having screw-threaded orifices at its opposite ends, a right-angled bar-arm having a guide-channel provided in its opposite

vertical sides, a slide-member having flanges adapted to freely engage said channels, clamp-devices mounted on the said right-angled bar-arm, and means for regulating and sustaining the said clamp-devices in either open or in closed position, substantially as shown and described.

HENRY KRUG.
JOSEPH DODD.
